MATTRESS MAKING MACHINERY

Filed March 18, 1931

UNITED STATES PATENT OFFICE

MILTON LOUIS SHIFMAN, OF EAST ORANGE, NEW JERSEY, ASSIGNOR TO SHIFMAN BROS., OF NEWARK, NEW JERSEY, A CORPORATION OF NEW JERSEY

MATTRESS MAKING MACHINERY

Application filed March 18, 1931. Serial No. 523,800.

This invention relates to improvements in wire spring mattress making machinery, and relates more particularly to improvements in machinery for weaving the mattress springs together into a mattress unit. 5

One of the objects of the invention is to provide an improved machine for weaving the upper and lower horizontal coils of a mattress together.

10 A further object of the invention is to provide a machine for weaving the upper and lower horizontal coils of a mattress together by coil wire springs.

A still further object of the invention is 15 to provide means for properly spacing the vertical coils of a mattress and weaving them together by wire strips.

The invention also has other objects, all of 20 which will be hereinafter more particularly set forth and claimed.

In the accompanying drawing:

Figure 1 represents a perspective view of 25 the devices embodying my invention in operation and weaving the spaced coils of the mattress together and

Figure 2 represents a top plan view of two of the adjacent coils after they are woven together.

Wire mattresses have heretofore been constructed by arranging a series of helical wire springs side by side and binding the top and bottom coils together by a longitudinal coil spring wire. This binding or weaving operation has been accomplished with considerable difficulty as the coil springs do not naturally find their proper positions to coil about and bind together the adjacent contacting coils of the springs of two adjoining rows and must be therefore more or less guided by 30 hand, so that the end of the coil binding spring will start the proper movement about the two horizontal coils that are to be bound together. As it was necessary to rotate the coil binding spring at the same time that it 35 was guided, the operation was lengthy and a difficult one.

The present invention is intended to overcome the difficulties of such manufacture by rotating the binder coil spring by motor, and 40 automatically feeding it forward during its

rotation while at the same time retaining the full length of the binding coil in an extended position to prevent tangling or looping. The coil binding wires are, of course, extremely flexible, and if the forward feed is not held 55 under tension, which at the same time allows an automatic forward movement, the result is a looping or tangling of the unfed portion of the coil as it is rapidly rotated.

In the present machine tangling or looping 60 of the rapidly rotating coil is absolutely prevented and the coil, at the same time, allowed to automatically feed forward, only being guided by the operator at the time that the end of the coil is taking a "bite" on the next 65 succeeding pair of horizontal loops of the springs.

In the manufacture of coil spring mattresses, the coil springs 1 are arranged in 2 parallel rows upon tapered spindles 3, arranged along near one end of the work table or bench 2. With this arrangement, the two rows of springs arranged on the spindles are woven together top and bottom. These two rows of springs are then lifted from the 75 spindles and again dropped on the spindles with the last row woven on the innermost spindles and a fresh row of unattached springs on the outside row of spindles and the operation repeated. 80

As the weaving takes place, the width of the table 2, which is equal to the width of the mattress, supports the woven springs until the mattress is finally completed.

Any particular structure of coil springs 85 may be employed, either cylindrical or with a double tapered spiral as shown in the drawing.

The binding coils 5, of the spring wire are previously coiled in the spiral of sufficient 90 diameter to freely pass about the two adjacent horizontal coils 4, of two adjoining springs. These coils may either be arranged side by side, or one overlapping the other, as shown in Fig. 2.

The feeding forward of the binding coil 5, takes place automatically when the coil is rotated, as the coil being wound in a spiral automatically feeds itself by its grip on the coils 4, after the free end of the spring 5 has 100

been started about the two adjacent coils, by hand.

In order that both of the operator's hands may be free to start this movement of the coil 5, about the coils 4, the rotation of the spring 5 is controlled by a foot pedal 25, which runs along the entire length of the table 2 near the operating edge, and is supported by pivoted arms 28. The coil 5, when the operation starts, is secured at one end in a suitable form of chuck 6. This chuck 6 is rotated by a shaft which passes through a sleeve 29, which is mounted in a housing 16, containing the usual bevel gears, these gears in turn being operated by a flexible shaft 17. The shaft 17 is connected to one member of a clutch 19, this clutch being normally engaged by a coil spring 26, the remaining member of the clutch being connected to the continuously running motor 20, the motor clutch and other parts being mounted on a frame 22. One member of the clutch is provided with a grooved sleeve 18, which is engaged by the slotted arm of the bell crank lever 30 to throw the clutch in and out, in a manner well known in the art of clutches.

The bell crank lever is pivoted as at 21, and one of its arms 31 is slotted as at 32 to receive the vertical arm of a second bell crank lever 33 which is suitably pivoted on the frame 22, so that one of its arms 24 lies under the foot pedal rod 25.

It will be seen from the above that the clutch 19 is normally held in engagement by the spring 26, but that the foot pedal 25 when depressed will operate the bell crank lever 30, and move the clutch out of engagement to stop the rotation of the binding coil 5. As the coil 5 must be of a length equal to the length of the mattress to be manufactured, it will be seen that when the operation is first started on any particular row, that there is about 6 feet or more of this coil 5, and that if the coil were not suitably supported under tension, it would become tangled or snarled because of its rapid rotation. I secure the tension necessary for this purpose by providing a ring 34 which is pivoted by pins 35 to the sleeve 29 which surrounds the short shaft driving the chuck 6.

The ring 34 is carried by a frame 8, and this frame which is comprised of two bars forming approximately a triangle is provided at its upper end with a cross bar 9, this bar being journaled in two supports 10, secured to the ceiling of the room in which the machine is located. To a cross bar 12 of the frame 8, I secure one end of a cable 13, this cable in turn passing over two grooved wheels 14, secured to the ceiling 11. A suitable weight 15 is secured to the end of the cable 13.

By reference to Fig. 1 it will be seen that the weight 15 not only counter-balances the weight of the frame 8, housing 16, flexible

cable 17, and connecting parts, as well as the extended length of the spring 5, but has sufficient preponderance of weight to tend to move frame 8 to the right so as to always hold the spring 5, under sufficient tension, to prevent this spring when being rapidly rotated, starting to vibrate and jumping into snarls or loops, which, of course, would require undoing the work that had been done, in inserting a new binding spring.

In the weaving of the mattress with the mechanism above described, only a very slight pause or slowing up of the speed is necessary, as the operator guides the end of the spring 5 into each succeeding pair of loops 4. The operator simply has to guide the end of the spring 5 as the forward movement of the spring is automatic because of its rotation as before described. It will be seen from the above that the operator is standing almost directly over his work at the edge of the table, and that by binding one row of coils after another to this outside edge the bulk of the mattress as it grows, moves away from him, and is never interposed between him and his work.

As the spring 5 moves forward because of its spiral construction, the frame 8, of course is pulled down against the tension of the cable 13 until the spring 5 has bound both rows of springs 1 together for their entire lengths. The chuck 6 is then operated to release the end of the spring 5 and a fresh spring secured in the chuck at one end and the operation for the next row started. This operation continues until the mattress is completed. It, of course, will be understood that the springs 5 are previously wound in lengths equal to the length of the mattress to be manufactured, and are given the proper diameter to snugly encompass the two adjoining coils 4 when fed forward by the rotation of the spring.

Having thus described my invention, what I claim as new and desire to secure by Letters Patent is:

1. In a machine for manufacturing coil spring mattresses, the combination with means for holding mattress springs in rows, of a pivoted supporting frame movable towards and away from the spring supporting means, a weight for holding the frame normally away from the spring supporting means to keep a binding spring under tension, and binding spring rotating means mounted on the frame.

2. In a machine for manufacturing coil spring mattresses, the combination with means for holding the mattress springs in rows, of a rotating chuck for receiving the binding mattress spring, means for rotating the chuck and yielding means supporting the chuck to hold the binding spring under tension during its forward feed.

3. In a machine for manufacturing mattresses, the combination with means for sup-

porting mattress springs in rows, of a rotating chuck for receiving one end of a binding spring, a pivoted frame supporting the chuck, a motor and connections for rotating the chuck and a weight and cable for normally pulling the frame away from the mattress springs, but allowing it to be drawn towards them.

4. In a machine for manufacturing coil spring mattresses, the combination with means for holding the mattress springs in rows, of a chuck and connections for rotating a binding spring, yielding means for holding the chuck away from the mattress springs, a foot pedal, and mechanism controlled by the foot pedal for starting and stopping the chuck.

5. In a machine for manufacturing coil spring mattresses, means for holding the mattress springs in rows, devices for holding and rotating a binding coil, and means tending to pull the coil automatically away from the mattress but yielding to allow its forward feed to keep the rotating binding coil extended its full length.

6. In a machine for manufacturing coil spring mattresses, the combination with means for holding mattress springs in rows, of devices for holding and rotating a coil and automatic weight operated means for holding the coil extended but allowing it to yield when fed forward to be wound about the mattress springs.

7. In a machine for manufacturing coil spring mattresses, the combination with means for holding rows of mattress springs, of a device for rotating a binder spring, automatic means tending to pull the binding spring away from the mattress but yielding to allow it to feed forward, a fixed motor and flexible means for connecting the motor and the spring rotated device.

In testimony whereof I affix my signature.
MILTON LOUIS SHIFMAN.
